TABLE SLIDE

William A. Duncan, Statesville, N. C.

Application October 18, 1939, Serial No. 300,051

1 Claim. (Cl. 311—73)

The device forming the subject matter of this application is a slide mechanism for an extension table. The invention aims to provide novel means for mounting the rack and pinion with respect to the rails and the equalizing bar, to provide a device which will operate noiselessly, and to supply a structure in which working parts will be housed from view.

It is within the province of the disclosure to improve generally and to enhance the utility of devices of that type to which the present application appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in longitudinal section, a device constructed in accordance with the invention, mounted on a table;

Fig. 2 is a horizontal section, the device being collapsed;

Fig. 3 is a longitudinal section showing the device extended;

Figs. 4 and 5 are cross sections taken, respectively, on the lines 4—4 and 5—5 of Fig. 2;

Fig. 6 is a transverse section taken taken on the line 6—6 of Fig. 3;

Fig. 7 is an elevation showing a modification;

Fig. 8 is a longitudinal section of the structure shown in Fig. 7;

Fig. 9 is a cross section on the line 9—9 of Fig. 8;

Fig. 10 is a longitudinal section showing a modification;

Fig. 11 is a cross section of the structure depicted in Fig. 10.

Referring to the form shown in Figs. 1 to 6, the numeral 1 marks parts of an extension table top, and to the respective parts 1 are secured outer rails 2, provided upon their inner sides with longitudinal dovetailed grooves 3.

The numeral 4 designates an equalizing slide, disposed between the outer rails 2 and slideable with respect thereto, the rails 2 and the equalizing slide 4 preferably being of solid wooden construction. On its opposite sides, the equalizing slide 4 has longitudinal dovetailed grooves 5, facing the grooves 3 of the rails 2, as Figs. 4 and

5 will make manifest. The grooves 5 define, in the equalizing slide 4, a reduced rib 6, disposed between the grooves.

In the rails 2, at the bases of the grooves 3, are formed elongated seats 7, wherein are received the rectangularly disposed base flanges 8 of angle members including rack flanges 9 extended into the grooves 3 of the rails 2. In the grooves 3 of the rails 2 are secured first blocks 10, which are shaped to be received slidably in 10 the grooves 5 of the equalizing slide 4, thereby to aid in connecting the member 4 slidably with the rails 2. The blocks 10 are disposed diagonally with respect to each other, as can be seen in Fig. 2.

Second blocks 11 are secured in the grooves 5 of the equalizing slide 4, in diagonal relation to each other, the blocks 11 being slidably received in the grooves 3 of the rails 2, to aid in connecting the equalizing slide 4, slidably, to the 20 rails 2. The blocks 11 have longitudinal recesses 12, disposed at the bases of the grooves 3 in the rails 2 and adapted to receive the ends of the racks 9, when the table is extended, as shown in Fig. 3.

A slot 14 is formed in the rib 6 of the equalizing slide 4, and in the slot 14 is received a pinion 15, extended into the grooves 5 of the equalizing slide, the pinion being mounted to rotate on a shaft or pin 16, mounted in the equalizing slide, 30 but extended only part-way therethrough, so that the pin cannot drop out.

Noting Fig. 3 of the drawings, the table may be extended until the racks 9 come into contact with the blocks 11. When the table is extended, 35 as shown in Fig. 3, the racks 9 are received in the recesses 12 of the stop blocks 11. The construction is such, as shown in Fig. 3, that the racks 9 and the pinion 15 always are concealed.

In Figs. 7, 8 and 9, parts hereinbefore described 40 are designated by numerals already used, with the suffix "a". In this form of the invention, the racks 9a are located in longitudinal grooves 17 in the rails 2a, the slot 14a being located accordingly, as shown in Fig. 9. The grooves 17 45 are somewhat longer than the racks 9a, so that the pinion 15a may be engaged with the racks 9a, and the blocks 10a and 11a be permitted to be received in the grooves with which they coact, in the assembling of the device. In this 50 form of the invention, the elongating of the device is limited by a movable wooden rod 18 or the like, interposed between the blocks 10a and 11a.

In Figs. 10 and 11, parts hereinbefore described 55

have been designated by numerals already used, with the suffix "b." The characteristic feature of this form of the invention is that the racks 9b and the pinion 15b are made of hard fiber or 5 some similar material, an absolutely noiseless structure resulting. When fiber or its equivalent is used, it is desirable to have the racks 9b and the pinion 15b somewhat wider than are the corresponding parts in Figs. 7 to 9.

10 The various racks hereinbefore alluded to may be made in any desired way and of any preferred material.

15 The device is simple in construction, but will be found thoroughly advantageous for the ends in view. It will consummate the objects set forth in the opening portion of this specification.

Having thus described the invention, what is claimed is:

20 Extension table structure, comprising rails and an equalizing slide therebetween, the slide having

a slot, the rails and the slide having dovetailed grooves there being seats in the rails, at the bases of the grooves thereof, first blocks fixed in the grooves of the rails and slidable in the grooves of the slide, second blocks fixed in the grooves 5 of the slide and slidable in the grooves of the rails, all blocks conforming in transverse section to the grooves, to hold the rails and the slide against lateral separation, angle members comprising 10 rack flanges extended into the grooves of the slide, and base flanges secured in the seats of the rails, and a pinion located in the slot and meshing with the rack flanges, the pinion being supported for rotation on the slide, the second blocks having longitudinal recesses, disposed at 15 the bases of the grooves of the rails and receiving the ends of the rack flanges when the table structure is extended.

WILLIAM A. DUNCAN. 20
